The ornamental design for a display tower for compact discs, as shown and described.

DESCRIPTION

FIG. 1 is a perspective view of a display tower for compact discs showing my new design, the other sides being identical thereto;

FIG. 2 is an enlarged top plan view thereof;

FIG. 3 is a side elevational view of a module;

FIG. 4 is an enlarged bottom plan view thereof; and,
FIG. 5 is an enlarged fragmentary sectional view taken along line 5—5 of FIG. 3.

The broken line showing of compact discs in FIGS. 1, 3 and 5 is for illustrative purposes only and forms no part of the claimed design.
